DESIGN FOR A REFRIGERATOR

Wilbur Henry Adams and Marc Resek, Cleveland Heights, and John A. Dahlstrom, Bay Village, Ohio, assignors to Perfection Stove Company, Cleveland, Ohio, a corporation of Ohio

Application January 30, 1936, Serial No. 60,908

Term of patent 14 years

To all whom it may concern:

Be it known that we, (1) Wilbur Henry Adams, (2) Marc Resek, and (3) John A. Dahlstrom, citizens of the United States, residing at (1 and 2) Cleveland Heights and (3) Bay Village, in the county of Cuyahoga and State of Ohio, have invented a new, original, and ornamental Design for Refrigerators, of which the following is a specification, reference being had to the accompanying drawing, forming part thereof, and wherein Fig. 1 is a front elevation, Fig. 2 a side elevation, and Fig. 3 a plan view of a refrigerator showing our new design. The side opposite that shown in Fig. 2 is the same as the one revealed therein.

We claim:

The ornamental design for a refrigerator as shown and described.

WILBUR HENRY ADAMS.
MARC RESEK.
JOHN A. DAHLSTROM.
